UNITED STATES PATENT OFFICE.

THOMAS KELLY, OF CLEVELAND, OHIO.

COMBINED BRACE AND TIE ROD FOR CONCRETE FORMS.

Application filed March 28, 1923. Serial No. 628,208.

To all whom it may concern:

Be it known that I, THOMAS KELLY, a citizen of the United States, and a resident of Cleveland, county of Cuyahoga, and

5 State of Ohio, have invented a new and useful Improvement in Combined Braces and Tie Rods for Concrete Forms, of which the following is a specification, the principle of the invention being herein explained and the 10 best mode in which I have contemplated applying that principle, so as to distinguish it from other inventions.

The present improved device is designed more particularly for use in the erection of 15 forms for casting or molding monolithic concrete structures, such as walls and the like, wherein forms of various kinds are employed, the parts of which require to be temporarily secured in place and are then 20 taken down after the concrete has sufficiently set. Thus in building walls, abutments and the like, such forms ordinarily consist of a series of planks which are placed on edge one above the other so as to define 25 a space of the required dimensions into which the concrete in plastic state is then poured. It is important that such planks or equivalent forms should be readily removable when they have fulfilled their function 30 without damage either to the concrete in course of setting or to themselves, if such forms are to be used over again.

The object of the invention accordingly is to provide a simple and compact device 35 for thus securing in place forms of the kind described whether used in the construction of walls, floors, ceilings, sidewalks, roadways or any structure adapted to be made of concrete by pouring the same into a temporary form or mold.

To the accomplishment of the foregoing and related ends, the invention, then, consists of the means hereinafter fully described and particularly pointed out in the 45 claims, the annexed drawings and the following description setting forth in detail certain mechanism embodying the invention, such disclosed means constituting, however, but one of various mechanical forms in

which the principle of the invention may be 60 used.

In said annexed drawings:—

Fig. 1 is a vertical transverse section through a composite form of the type ordinarily used in constructing concrete walls, 55 etc., my improved combination brace and tie rod being shown as in use to retain the parts of the form in proper place; Fig. 2 is a vertical section on larger scale (approximately full size) of one end of such 60 combination tie rod and brace as applied to the adjacent form part; Fig. 3 is a horizontal section of the same, the plane of such section being indicated by the line 3—3, Fig. 2; Fig. 4 is a sectional detail on the 65 same plane as Fig. 2, but showing the parts of the device in a different operative condition; and Fig. 5 is a view, similar to that of Fig. 1, but showing the adaptation of the device for use in sustaining a horizontally 70 instead of a vertically extending form, specifically a form for molding concrete about a horizontal beam or the like.

Where, as illustrated in Fig. 1, a series of vertically superposed planks 1 is required to be held in place, a corresponding series of vertically spaced devices will be employed, each consisting of a transversely disposed rod 2 and a pair of suitable keepers or locks whereby the ends of such rod are 75 secured to the inner faces of the adjacent planks. Preferably, as shown in Fig. 2, the devices are thus secured to the planks adjacent the joints therebetween so as to assist in imparting stability to the form 80 structure, but this is not an essential feature of the invention.

Each lock in its preferred form comprises a housing 3 of general frusto-conical form externally that is open at its larger end and is formed at its smaller end with an aperture 4 just large enough to easily admit the corresponding end of a rod 2. The latter, it will be noted, is formed with a transverse notch or recess 5 that is adapted to be engaged by an offset projection 6 on a dog or keeper 7 pivotally mounted in the housing about a transverse axis 8. Such dog

or keeper is further provided with an apertured opening 9 that lies to one side of such pivotal axis and in the normal or locking position of the device is in substantial alignment with rod 2.

The disposition of parts is such that when the end of the rod 2 is inserted through aperture 4 and the housing 3 is thereupon pressed against a flat surface, such as the 10 face of one of the planks 1, it will be rotated into position where the projection 6 will interlock with the notch 5 in such rod end. In order to retain the housing and keeper thus in locking position, a bolt 10 15 is employed which is threaded at both ends, the inner end being adapted to engage the aperture 9 in said keeper, while the outer end after passing through an aperture 11 in the plank passes through an apertured plate 20 or washer 12 and is engaged in a nut 13, as shown in Figs. 2 and 3. The aperture 11 in the plank is preferably located near one edge thereof so that both such housing 3 and plate or washer 12 will overlie the joint 25 between such plank and the edge of the adjacent plank.

When the form is erected, as illustrated in Fig. 1, a considerable degree of rigidity is imparted thereto by the employment of 30 my improved locking means particularly since, as will be observed, the rods 2 are held in the respective housings 3 against endwise movement in either direction. In other words, they serve both as tie rods and 35 braces to hold the planks or equivalent side members of the form in proper place.

When it is desired to remove the component parts of the form, the nuts 13 are loosened and removed, along with the 40 washers 12, from the outer ends of bolts 10. The inner ends of such bolts, however, remain in threaded engagement with the corresponding keepers 7, and the latter are thus in turn held in locking engagement with the ends of rods 2 until the planks 1 are actually removed for until 45 such removal occurs, the keepers cannot rock on their axes 8. However, after the keepers are thus disengaged the housings 50 3, due to their form, may be readily withdrawn from the concrete structure and likewise the rods 2, unless it be preferred to leave them remain in such structure. The recesses formed in the surface of the concrete by the housings, may then, if desired, be plastered over so as to leave a smooth 55 surface.

Instead of being employed merely to secure together vertically superposed form 60 parts, a box or trough-like form may be suspended from a beam 15 by employing angularly bent rods 16 instead of the straight rods 2, the upper ends of such rods

hooking over such beam, while their lower ends project outwardly and are notched for engagement by the keepers located in the respective housings 3 just as before. The form in this case will comprise two side members 17 and a bottom member 18 that is interlocked with said side members so 65 that it will drop out when the latter are removed. Numerous other adaptations of the device will readily suggest themselves where forms of different kinds from the two illustrated are to be erected. The device is extremely simple and compact in its construction, cannot be jammed by the concrete and yet cannot be unlocked until the form parts, to which it is attached, have been first taken down. Finally, the entire device 70 including the rods, except where of the special construction as shown in Fig. 5, may be entirely removed.

Other modes of applying the principles of my invention may be employed instead of 75 the one explained, change being made as regards the mechanism herein disclosed, provided the means stated by any of the following claims or the equivalent of such 80 stated means be employed.

I therefore particularly point out and distinctly claim as my invention:

1. In a device of the character described, the combination with a rod; of a lock 90 adapted to secure an end of such rod to the wall of a form or the like, such lock including a housing, a keeper movably mounted therein, said keeper and such rod-end being formed for locking inter-engagement in one position of said keeper, and 95 positively acting means for maintaining said keeper in such position.

2. In a device of the character described, the combination with a rod; of a lock 100 adapted to secure an end of such rod to the wall of a form or the like, such lock including a housing, a keeper movably mounted therein, said keeper and such rod-end being formed for locking inter-engagement in one position of said keeper, and a 105 bolt adapted to pass through the adjacent form-wall and to have threaded engagement with said keeper whereby the latter may be maintained in such rod-interengaging position.

3. In a device of the character described, the combination with a rod; of a lock adapted to secure an end of such rod to the wall of a form or the like, such lock including a housing open at one end and provided at the other with an aperture adapted to admit such rod-end, a keeper pivotally mounted in the open end of said housing, said keeper and such rod-end being formed with locking elements adapted to inter-engage when 110 said keeper lies wholly within said hous- 115 ing.

ing, and means adapted to secure the latter against the form-wall so as to maintain said keeper in such position.

4. In a device of the character described, the combination with a rod; of a lock adapted to secure an end of such rod to the wall of a form or the like, such lock including a housing open at one end and provided at the other with an aperture adapted to 10 admit such rod-end, a keeper pivotally mounted in the open end of said housing,

said keeper and such rod-end being formed with locking elements adapted to inter-engage when said keeper lies wholly within said housing, and a bolt adapted to pass 15 through the adjacent form-wall and to have threaded engagement with said keeper whereby the latter may be maintained in such rod-interengaging position.

Signed by me, this 26th day of March, 20
1923.

THOMAS KELLY.
